UNITED STATES PATENT OFFICE.

WILLIAM P. CARSTARPHEN, OF DENVER, COLORADO.

HEADLIGHT.

Application filed July 9, 1925. Serial No. 42,524.

This invention relates to improvements in headlights and has reference more particularly to a reflector adapted to be secured within the ordinary headlight reflectors.

In United States Letters Patent No. 1,542,988 granted to me on June 23, 1925, I have shown and described a reflector of a peculiar construction and have shown means for securing the same in place within a headlight casing. As the improved reflector is intended to be applied to and employed in connection with headlights that are already equipped with ordinary paraboloidal reflectors, it has been necessary to provide a construction that can be readily secured in place and which can be applied to headlights of various diameters. As there are a large number of different makes of automobiles and as each make has a special type of headlight it is evident that an enormous stock of reflectors would have to be carried by a dealer if he were to be in position to fit all sizes and makes of lamps. It would also be necessary for the manufacturer to have a large number of dies. In order to obviate these difficulties, I have produced an improved reflector that is so constructed that it can be secured to the ordinary reflector with which the headlight is equipped and which will fit a large number of different sizes of lamps.

My improved reflector consists of a concave reflecting surface formed in the manner described in the above identified patent. The reflector has a flat circular flange at its outer end and a tubular portion extending axially from the rear thereof. The circular flange is adapted to fit within the old reflector and to contact with the inner surface near the front edge thereof. The tubular member is intended to project through an opening in the rear of the old reflector and to be secured to the latter by means of a nut or other clamping means.

In order to describe my invention with greater clearness and more particularity I shall have reference to the accompanying drawing in which the invention has been illustrated and in which:

Fig. 1 is a section taken on line 1—1, Fig. 2;

Fig. 2 is a section taken on line 2—2, Fig. 1 and

Fig. 3 is a section taken on line 3—3, Fig. 2.

Numerals 1 represents any ordinary lamp housing; 2 the ring by means of which the lens 3 is held in place and 4 the ordinary reflector which is usually of parabolic form. The reflector 4, ring 2 and housing 1 are merely representative of corresponding members found in all headlights now in the market. The housing 1 has an inwardly extending tubular projection 5 in which the lamp socket 6 is slidably secured by means of the screw 7 and spring 8. It is well known that the dispersion of light from a parabolic reflector is objectionable for the reason that if the light source is not exactly at the focus they blind the drivers of approaching machines and if the light is exactly at the focus, then they project a cylindrical beam of light of the same diameter as the reflector, which is useless for illuminating the road. In the patent above identified I have described a reflector that gives a good light on the road and does not produce a blinding glare and in this drawing I have indicated this reflector by the numeral 9. It is my intention to secure this reflector in place within the reflector 4 and I accomplish this in the following manner: Reflector 9 has a circular flange 10 extending outwardly from its front end. The diameter of this flange is somewhat less than the maximum internal diameter of the reflector 4 so that when the reflector 9 is inserted within the reflector 4, the flange 10 will engage the inner surface of the latter near the front edge thereof. Reflector 9 is provided at its rear with an axially extending tubular member 11 that is of sufficient length to project through the axial opening 12 of the reflector 4. The tubular member 11 is threaded and after it has been inserted through the opening 12, a nut 13 is applied to it in the manner shown in Figs. 2 and 3. It is obvious that by tightening the nut 13, the reflector 9 can be secured in place within the reflector 4, as it will produce a force that will pull the flange 10 against the surface of the reflector 4. As the inner surface of a parabolic reflector makes quite an angle with the axis of the reflector, it is evident that by properly selecting the diameter of the flange 10 of the reflector 9, the latter can be used with a large number of different sizes of parabolic reflectors so that by keeping in stock reflectors having flanges of, say, three different

diameters, it is possible to fit almost any of the ordinary sized headlights. The flange 10 is provided with a mark 14 that coincides with the major axis of the reflector and by means of which the reflector is adjusted about its axis. It is evident that with a reflector constructed in the manner described, any desired rotary adjustment can be made, whereas, if the reflector were provided with bayonet connection for securing it in place, rotary adjustment could not be made.

Although I have shown a reflecting surface of a peculiar construction, it is evident that my fastening means may be employed in connection with any kind of a reflecting surface and can be employed with advantage wherever a different kind of a reflecting surface is to be applied to a headlight.

The opening 12 is usually reamed out and as all ordinary reflectors are provided with an axial opening it is only necessary to en-

large this to the proper size to receive the tubular member 11.

Having now described my invention, what I claim as new is:

A headlight comprising, in combination, an outer housing, a concave reflector located within said housing, a second concave reflector of smaller size than the first and adapted to be secured in place within the first reflector, said second reflector having a circular flange extending outwardly at its open end, the diameter of said circular flange being less than the maximum inside diameter of the first mentioned reflector whereby it will contact with the inner surface of the first mentioned reflector at some point within the same and means comprising a threaded tubular member for securing said reflectors together.

In testimony whereof I affix my signature.

WILLIAM P. CARSTARPHEN.
